(57) **CLAIM**

The ornamental design for a muscle-tendon relax device, as shown and described.

DESCRIPTION

FIG. 1 is a perspective view of a muscle-tendon relax device, showing my new design;

FIG. 2 is a front view of the muscle-tendon relax device;

FIG. 3 is a rear view of the muscle-tendon relax device;

FIG. 4 is a left side view of the muscle-tendon relax device;

FIG. 5 is a right side view of the muscle-tendon relax device;

FIG. 6 is a top view of the muscle-tendon relax device; and,

FIG. 7 is a bottom view of the muscle-tendon relax device.
